FLUID PUMP

Leroy A. Thomson, La Crosse, Wis., assignor to
Bump Pump Company, La Crosse, Wis.

Application October 25, 1937, Serial No. 170,882

3 Claims. (Cl. 103—126)

This invention relates to pumps and more particularly to positive displacement pumps.

One object of this invention is to provide a new pump construction. Another object is to provide a pump which will operate efficiently at wide ranges of speed. A further object is to provide a pump which will deliver a smooth flow of fluids with very little pulsation. Another object is to provide a pump which is especially adaptable for use in the treatment of food products. Another object is to construct a pump which will have very little leakage under a standing pressure head. Another object is to construct a pump with separate driving and operating compartments. Another object is to provide a pump which is readily separable into elemental portions. A further object is to provide a pump construction which will prevent a compression of fluid between the impeller ends. A further object is to provide a pump which will be free of compression knocks. Other objects and advantages of this invention will appear more fully in the following description taken in connection with the accompanying drawings.

In the drawings, wherein like numerals represent corresponding parts in the various figures, Fig. 1 is a right hand end elevation of the pump incorporating features of this invention. Fig. 2 is a left hand end elevation view. Fig. 3 is a longitudinal vertical cross section through the pump with parts broken away. Fig. 4 is a view taken on the line 4—4 in Fig. 3. Fig. 5 is a view taken on the line 5—5 in Fig. 3. Fig. 6 is a view taken on the line 6—6 in Figs. 3 and 5. Fig. 7 is a three corner perspective showing one of the impellers. Fig. 3 corresponds to a section on the lines 3—3 in the other figures.

Considering the drawings in greater detail, the pump comprises a driving means, suitable impellers, and a housing 10 having inlet and exhaust openings 11 and 12 respectively. The impeller housing is so arranged that the impellers or pistons always lock the chamber in a positive manner to prevent any pulsation in the movement of the liquid.

The pump housing 10 comprises an impeller housing 13, the impeller cover or faceplate 14, the gear housing 15, and the gear housing cover or faceplate 16. These parts are arranged to be secured together at abutting surfaces so as to maintain the elemental parts of the pump in a definite position. The impeller cover is aligned with respect to the impeller housing so that it will be maintained in a definite position by means of the dowel pins 17 and 18. These pins are ar-

ranged to fit into appropriate recesses in the two members so as to always properly align the parts when they are assembled.

The impeller cover 14 is secured to the remaining portions of the pump by means of clamps 19 and 20, the former of which is pivotally secured upon the impeller housing at 21 and the latter of which is pivotally secured upon the gear housing 22. The upper and lower clamps are substantially of the same construction but are slightly different in size. The upper clamp 19 comprises two arms 23 and 24 pivotally secured to the boss 21 by the bearing pin 25. At the ends of the arms 23 and 24 away from the pivot 25 is secured a cam lever 26 coupled to the two arms by the pivot pin 27. The lever 26 is provided with cam surfaces as at 28 and is arranged so that it may act as a yoke encompassing the boss 29 on the cover member. After the yoke is dropped over the boss, cam lever 26 is turned in a clockwise direction tightening the cam against the outer surfaces 30 and 31 to securely lock the cover to the impeller housing. The impeller cover 14 has a similar boss 32 at the bottom. A pair of lever arms 33 and 34 are pivoted to the boss 22 on the gear housing by means of the pivot pin 35. The opposite ends of the two arms are connected together by a cam lever 36 which is pivotally secured thereto by the cam pin 37. The cam surfaces 38 of this lever abut against one face 39 of the boss and the face 40 of the cover.

The gear housing is provided with a bottom flange 41 upon which the impeller housing member 13 is mounted and secured through its oppositely extending base flanges 42 and 43 by means of the holdfast means 44. The opposite face 45 of the impeller housing is provided with a plurality of holes 46 receiving dowel pins 47 for centering the two parts with respect to each other. They are then securely locked together by the cap screws 48, extending through the downwardly extending flange 49 of the gear housing and into the abutting portion 50 of the impeller housing and the tie screws 53. The abutting faces 51 and 52 respectively of the gear housing and gear housing cover are secured together by the cap screws 54 and 55. It of course will be readily understood that gaskets 56 and 57 may be placed between the abutting faces of the impeller housing and impeller housing cover, and between the abutting faces of the gear housing and gear cover respectively. The impellers 58 and 59 are press-fitted upon their respective stub shafts 60 and 61 and are pressed from right to

left as viewed in Fig. 3 until they abut against the annular flange 62 integral with each stub shaft. The hub 63 of the impeller, is then keyed to the shaft by means of at least one Woodruff key 64. The stub shaft is then inserted through the sleeve bearing 65 which is fitted into the annular bearing boss 66, the latter being integral with the impeller housing 13. The bottom impeller will also be mounted as just described in the same manner as described in connection with the upper impeller after which the impeller housing cover 14 will be locked to the impeller housing. The impeller housing contains two similarly shaped hollow annular bosses 67 arranged to provide appropriate packing holders for the stub shafts. The impeller housing cover contains a similar set of oppositely extending bosses 68. After the parts have been assembled as thus far described, packing 69 is inserted about the stub shaft and in the counterbored recesses of the bosses 68 after which the packing is locked in place by means of the packing glands 70. Packing 71 is similarly arranged about the stub shafts within the counterbores of the bosses 67 wherein it is secured in place by the packing glands 72.

The outer ends of the stub shafts are supported by ball bearings. The impeller housing cover is arranged with inner and outer spaced walls 73 and 74. The inner walls 73 are provided with spaced circular recesses 75 in which the hubs 63 of the impeller are received. The two walls are spaced apart by the upper and lower cover frame portion 76 and 77 respectively. The outer wall 74 is also provided with two spaced similarly shaped counterbores 78 for supporting the bearings. The inner diameter of the bores 78 is sufficiently large to allow the packing glands 70 to be placed upon the stub shafts. The hole is then bored with a larger diameter portion 79 into which the outer annulus 80 of the bearing is received. The inner annulus 81 of the bearing is fastened to the end of the shaft 60 by means of the shaft nuts 81', and is spaced from the outer annulus by means of the bearing balls 82. The bearings are finally retained in place by means of the bearing plug members 83 each having an annularly extending flange 84 arranged to fit within the recess 79 and to abut against the outer annulus 80 of the bearing. These plug members are secured in place by a plurality of machine screws 85. The lower plug is similarly shaped and is secured in the same manner. It will be appreciated that the impellers and the various parts used to retain them in place are so organized as to be interchangeable, in other words, the entire impeller assembly for the upper impeller in Fig. 3 can be substituted for the lower impeller in Fig. 3 and vice versa. In this manner, a number of different parts for the pump may be very materially reduced.

The impeller housing contains a recess 86 comprising two intersecting annular chambers 87 and 88 being annular in shape in view of the central bosses 66. The central bosses are provided with arcuate oppositely facing recesses 89 concentric with the outer wall of the corresponding impeller chambers 87 and 88. The interconnecting wall portions 90 of the housing are substantially straight and parallel to each other. The inlet and exhaust pipes 11 and 12 are threaded for standard pipe connections and have central bores 91 which extend into the impeller chambers by means of the under-cut portions 92. These port bores are cut with definite di-

5 mensions to contribute to the efficiency and performance of the pump. The counterbored ports 92 allow the fluid to flow in freely on the intake stroke of the impeller and when the impeller cuts across the port at the end of the intake stroke the bore in effect gives to the impeller end a shearing motion across the fluid column resulting in a smooth, quiet, pump operation. The arrangement of the counterbores and the impeller ends also prevents any compression of fluid 10 between the impeller ends thereby preventing a condition which if present would cause an objectionable knock.

The operation of this positive displacement pump will now be described in greater detail. 15 The impellers 58 and 59 are arranged to be driven in opposite directions as indicated by the arrows in Fig. 5. The position of the parts as shown in Fig. 5 corresponds to approximately the middle of the intake stroke for the impeller 58 and 20 approximately the middle of the exhaust stroke for the impeller 59. Assume the trailing edge 93 of the impeller 58 to have just uncovered the counterbore 92 and to have created a partial vacuum thereby sucking in fluid behind the face 25 93. The impeller continues to rotate in a clockwise direction and continues to draw fluid into the chamber 87 until the leading face 94 seals the inlet 92. The continued rotation of the impeller finally uncovers the counterbore 91 allowing the fluid to be forced through the outlet 12. With the impeller 58 at the beginning of its intake stroke, it will be observed that the lower impeller 59 is in a sealed position. On the one hand, resulting from the sliding engagement of 30 the impeller with the boss 66, and on the other hand by the engagement of the end portions of the impeller 59 in engagement with the walls of its cylinder 96 at the points 95 and 96. While the lower impeller is in a sealed position, the upper impeller is creating a vacuum causing fluid 35 to be drawn into the space left by the displacement of the impeller during its rotation. With the impellers in the position shown in Fig. 5 the upper impeller is sealed against the lower boss at 40 the point 97 while the lower impeller is sealed at the point 98. This arrangement allowing the two impellers to be sealed at the same time, together with the design of the port bores, prevents any oscillations of the pumped fluid in the impeller chamber. The condition of fluid oscillation just mentioned is quite prevalent in the usual 45 rotary pumps and is a condition which is to be avoided.

When the impellers are in a substantially horizontal position with their arcuate members facing downwardly, the upper impeller is beginning to take in fluid whereas the lower impeller has just completed its last intake and is about ready to begin exhausting fluid. When the two impellers are in the horizontal position with their arcuate shapes facing upwardly the upper impeller has just completed its last intake and the lower impeller is just beginning to take in fluid while at the same time completing its exhaust 50 from the previous intake.

After the upper impeller has completed its intake it continues rotation and covers the port 91 and allows it to exhaust fluid which has been entrained behind the face 93. The leading face 70 94 then acts as the face of the piston forcing the fluid out of the pump. The continuous rotation of the parts creates a continuous series of cycles of intake and exhaust for each impeller.

In order to drive the impellers in an opposite 75

direction a gear drive is provided which may be driven from any suitable means coupled to the driving stub shaft 99. This latter shaft is supported in the sleeve bearing 100 carried by the boss 101 of the gear housing and by the roller bearing 102 carried by the boss 103 of the gear cover. The inner end of the bearing 100 is sealed by the oil seal 104 and the outer end of the shaft by another oil seal 105. A standard spur gear 106 is fastened on the stub shaft 99 by a Woodruff key 107 and is arranged to mesh with the spur gear 108 keyed at 109 upon the driven stub shaft 110. The right hand end of each of the gear stub shafts 99 and 110 is irregularly cut at 111, 112 respectively and arranged to engage a complementary portion on the shafts 60 and 61. After the two shafts are placed in engagement the joint can be covered by means of the sleeve 113 which may be locked by set screws to one or both shafts or which may be merely secured in place by a tie fit.

The inner annulus 114 of the bearing 102 is spaced from the gear wheel 106 by a spacing sleeve 115. The bearing is secured in place by the threaded plug member 116.

The lower gear shaft 110 is arranged to fit within a similar sleeve 100 and to be concealed by the oil seal 104. The lower bearing 102 is spaced by the gear wheel, by the spacing bushing 115 and is locked in place by the bearing plug 117. The outer end of the stub shaft 110 is covered by the expansion plate 118 which both seals the shaft and allows for any expansion which may occur.

The gear housing and gear cover form a closed oil reservoir 119 having a bottom drain opening 120 and a filling opening 121. The oil level is maintained sufficiently high so as to feed the oil ports 122 and 123.

The arrangement of the parts is so organized that the lubrication of the gear drive and the lubrication of the various bearings can be accomplished without allowing any oil or other lubricant to get into the impeller compartments. In this way a very efficient pump is provided which can be used in connection with foods such as milk etc. without any danger whatsoever of contamination being present.

Although the preferred embodiment of the invention is shown and described, variations coming within the true spirit and scope of the same are to be determined by the appended claims.

What I claim is:

1. A rotary pump comprising a gear housing, gears in said housing, extensions carried by said housing, an L-shaped member integral with one of said extensions, a pair of parallel shafts connected to said gears, an impeller housing engaging said extensions and said L-shaped member, means securing said impeller housing to said extensions, a pair of impellers rotatable in said impeller housing and connected to said shafts, said impeller housing having an inlet and outlet port,

and also having an open side, a cover for said open side of said impeller housing, outwardly projecting arms carried by said cover, each of said arms having cam engaging notches, pairs of links pivotally carried by said impeller housing and said L-shaped member, a cam member pivotally disposed between each pair of links and engageable in a notch to detachably lock said cover in applied position, and an operating lever secured to each cam. 5

2. A rotary pump comprising a gear housing, gears in said housing, extensions carried by said housing, an L-shaped member integral with one of said extensions, a pair of parallel shafts connected to said gears, an impeller housing engaging said extensions and said L-shaped member, means securing said impeller housing to said extensions, a pair of impellers rotatable in said impeller housing and connected to said shafts, said impeller housing having an inlet and outlet port, 10 15 and also having an open side, a cover for said open side of said impeller housing, outwardly projecting arms carried by said cover, each of said arms having a cam engaging notch in the outer side thereof, one wall of each notch being substantially horizontal and another wall under cut and inclined to the vertical, pairs of links pivotally carried by said impeller housing, and said L-shaped member, a cam member pivotally disposed between each pair of links and engageable in a notch to detachably lock said cover in applied position, each cam member when in operative position engaging in the angle between the walls of a notch, and an operating lever secured to each cam. 20 25 30 35

3. A rotary pump comprising a gear housing, gears in said housing, extensions carried by said housing, an L-shaped member integral with one of said extensions, a pair of parallel shafts connected to said gears, an impeller housing engaging said extensions and said L-shaped member, means securing said impeller housing to said extensions, a pair of impellers rotatable in said impeller housing and connected to said shafts, said impeller housing having aligned inlet and outlet ports and an open side, a portion of said impeller housing forming a partition extending partly across the confronting ends of said ports, each of said impellers being so disposed in said impeller housing as to project partially across a port and to engage against said partition, a cover for said open side of said impeller housing, outwardly projecting arms carried by said cover, each of said arms having cam engaging notches, pairs of links pivotally carried by said impeller housing and said L-shaped member, a cam member pivotally disposed between each pair of links and engageable in a notch to detachably lock said cover in applied position, and an operating lever secured to each cam. 40 45 50 55 60

LEROY A. THOMSON.
